US00D808007S

(12) **United States Design Patent** (10) **Patent No.:** **US D808,007 S**
(45) **Date of Patent:** **** Jan. 16, 2018**

(54) **WEARABLE INHALER**

(71) Applicant: **Martega Group LTD,**
Southend-On-Sea (GB)

(72) Inventor: **Maxwell Denega**, Southend-On-Sea
(GB)

(73) Assignee: **Martega Group LTD,**
Southend-On-Sea (GB)

(**) Term: **15 Years**

(21) Appl. No.: **29/597,056**

(22) Filed: **Mar. 14, 2017**

(51) LOC (11) Cl. **29-02**

(52) U.S. Cl.

USPC **D24/110**

(58) **Field of Classification Search**

USPC D24/108, 110, 167, 168, 186; D14/344;
D11/2

CPC A45F 2005/008; A61M 15/009; A61M
15/0021; A61M 15/0001; A62B 25/00

See application file for complete search history.

LLP

(57) **CLAIM**

The ornamental design for a wearable inhaler, as shown and
described.

DESCRIPTION

FIG. 1 is a front perspective view of a wearable inhaler
showing the new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a rear perspective view thereof.

The broken lines in the drawings depict portions of the
wearable inhaler that form no part of the claimed design.

1 Claim, 6 Drawing Sheets
